UNITED STATES PATENT OFFICE.

EDWARD L. GIERSDORF AND WILLIAM E. FARMER, OF MONROE, NEBRASKA.

PREHEATER.

1,273,767.

Specification of Letters Patent. Patented July 23, 1918.

Application filed April 19, 1917. Serial No. 163,252.

To all whom it may concern:

Be it known that we, EDWARD L. GIERSDORF and WILLIAM E. FARMER, citizens of the United States, residing at Monroe, in the county of Platte and State of Nebraska, have invented certain useful Improvements in Preheaters, of which the following is a specification; reference being had therein to the accompanying drawing.

- 10 The present invention has reference generally to improvements in that class of inventions known as internal combustion engines and more particularly relates to a preheater for internal combustion engines.
- 15 As the primary aim and object, the present invention resides in the provision of a heating attachment for the intake manifold of a gas engine for heating the intake pipe to consequently assure of a thorough vaporization of gasoline or the like as it is introduced into the cylinders of the engine, thus increasing the efficiency of the actuation of the engine.

More particularly, the present invention includes the provision of a novel fuel receiving receptacle as well as improved means for attaching the receptacle in a suspended position beneath the intake manifold so that the flame issuing from the receptacle will 30 be directed against the manifold.

It is a more specific object of the present invention to provide absorbent means in the receptacle for preventing splashing and spilling of the fuel; to provide reticulated means for maintaining an even flame; and to provide a movably mounted cover for removably closing the receptacle so as to smother and thereby extinguish the flame when it is so desired.

40 Among the other aims and objects of the invention, may be recited the provision of a device of the character mentioned with a view to compactness, and in which the number of parts are few, the construction simple, the cost of production low and the efficiency high.

Other objects as well as the nature, characteristic features and scope of this invention will be more readily apparent from the 50 following description taken in connection with the accompanying drawings and pointed out in the claim, forming a part of this specification.

The preferred embodiment of this invention is clearly illustrated in the accompanying drawings, in which:

Figure 1 is an elevation showing two of the heating attachments applied on the opposite portions of the intake manifold.

Fig. 2 is an enlarged front elevation of 60 the invention partly in longitudinal section.

Fig. 3 is a central transverse sectional view of the device, the cover being shown in an open position, while the dotted lines indicate the cover in a closed position. 65

Similar characters of reference are employed in all of the above described views, to indicate corresponding parts.

Referring now, more particularly, to the accompanying drawings, there is provided a 70 receptacle of an oblong configuration including side walls 1 with a bottom 2 connected to the lower edge of the side walls by means of the flange 3 which engages the correspondingly shaped edge of the side 75 walls. This receptacle is designed for receiving a suitable liquid fuel. In attaching the receptacle in position an upwardly extending arm 4 is formed integral the side wall intermediate the ends and has an opening 5 adjacent the upper end which is engaged by one of the bolts 6 which clamps the flanges 7 on the sections 8 of the intake manifold. As indicated in Fig. 1 two of these heating attachments are connected to 85 the respective ends of the flanges 7 on the respective ends of the Y-shaped section 8 of the manifold so as to maintain the receptacle in a suspended position beneath the manifold. 90

In order to prevent splashing and spilling of the fuel within the receptacle a piece of absorbent material 10 is arranged to rest on the bottom thereof while suitable reticulated means such as a piece of wire screen 11 95 having flange portions 12 is arranged to rest on the upper surface of the absorbent material 10 so that the flange portions are arranged between the edges of the absorbent material and the adjacent walls of the receptacle. The purpose of this piece of screen is to produce an even flame subsequent to the ignition of the fuel.

With a view toward providing suitable means for smothering and consequently extinguishing the flame, a movably mounted cover 13 is provided to engage the upper edge of the receptacle. A flange 14 depends from the edge of the cover and surrounds the receptacle. A hook 15 extends from the 105 intermediate portion of the flange adjacent one side of the cover and is movably engaged

in a slot 16 in the wall of the cover substantially intermediate the ends thereof and opposite the arms 4. This arrangement permits of a swinging of the cover to a closed or open position if desired. The flange 14 is preferably provided at a point opposite the hook with a recess 17 to permit of an effective engagement of the flange with the side walls of the cover about the arm 4.

10 In use, assuming that the device has been assembled in the manner described and attached in the position as indicated in Fig. 1 it is only necessary to swing the cover to a position as indicated in Fig. 3 and ignite 15 the fuel and the flames issuing from the receptacle are directed toward the under surface of the intake manifold so as to heat this pipe and consequently insure of an efficient vaporization of the mixture passing there-through preparatory to its introduction into 20 the cylinders of the engine (not shown).

It will be understood that the above description and accompanying drawings comprehend only the general and preferred embodiment of this invention and that various 25 minor changes in detail of construction, proportion and arrangement of the parts

may be made within the scope of the appended claim, and without sacrificing any of the advantages of this invention.

Having thus fully described our invention, what is claimed is:

A device of the character described including a fuel receiving receptacle, an attaching arm integral with and continuing upwardly from the upper edge of one side of the receptacle approximately intermediate the ends thereof, the opposite side of the receptacle being provided with a horizontal slot, a cover, a flange depending from and extending entirely about the edge of the cover for telescopic engagement with the receptacle, a hook depending from the flange and engageable in the slot for removably connecting the cover to the receptacle so as to assure of the smothering and extinguishing of the flame when desired, and the flange being cut away at a point opposite the hook to permit of a proper engagement of the flanged cover on the receptacle.

In testimony whereof we affix our signatures.

EDWARD L. GIERSDORF.
WILLIAM E. FARMER.
